Stanley Peters, San Diego, Calif.

Application August 1, 1957, Serial No. 47,182

Term of patent 14 years

(Cl. D22—5)

Fig. 1.

Fig. 2.

Fig. 3.

Fig. 1 is a side perspective view of a hair clipper comb plate attachment showing my new design, the side opposite thereto being substantially similar in appearance;

Fig. 2 is a bottom perspective view; and

Fig. 3 is a bottom plan view thereof.

The essential features of the design reside in the portions shown in solid lines on the drawing.

I claim:

The ornamental design for a hair clipper comb plate attachment, as shown and described.
